UNITED STATES PATENT OFFICE

MOTTEL CLAR, OF ENGLEWOOD, COLORADO

BATTERY CABLE TERMINAL

Application filed July 9, 1929. Serial No. 377,054.

This invention relates to a battery cable terminal and has for its principal object the provision of a terminal of this type which will insure a tight joint and which can be 5 quickly and easily detached from the battery post regardless of corrosion.

Another object is to provide a terminal in which the detachable portion can be cheaply and easily replaced should it become badly 10 corroded without the necessity of replacing the cable or sweating a new terminal thereupon.

A further object of the invention is to so construct the terminal that it can be easily 15 detached without the use of special tools, wrenches, etc.

Other objects and advantages reside in the detail construction of the invention, which is designed for simplicity, economy, and efficiency. 20 These will become more apparent from the following description.

In the following detailed description of the invention reference is had to the accompanying drawings, which form a part hereof. 25 Like numerals refer to like parts in all views of the drawings and throughout the description.

In the drawings:

Fig. 1 is a perspective view illustrating the 30 improved invention in the closed position.

Fig. 2 is a similar view illustrating it in the open position.

Fig. 3 is a detail plan view illustrating an alternate form of the invention.

35 In the drawings a battery cable is indicated at 10 and a typical battery post at 11. The invention comprises a main terminal member 12 arranged to partially surround the battery post 11 and having a cable sleeve 13

40 formed thereon for the reception of the battery cable 10. Upon the main terminal member 12 a bolt ear 14 is formed for the reception of a clamp bolt 15, as is usual in battery terminal constructions. The cable sleeve 13 is extended forwardly as shown as 16 and is provided with an opening or socket 17.

The remainder of the terminal comprises a hinged member 18 which is pivoted upon and 45 swings about the clamp bolt 15. The hinged member 18 is provided with a lug 19 which

engages in the socket 17 when in the closed position. A tool opening 20 is formed in the hinged member 18 to facilitate its operation.

In placing the terminal upon the battery post the lug 19 is inserted in the socket 17 55 and the complete terminal is slipped over the battery post 10 as indicated in Fig. 1. The clamp bolt 15 is then tightened to securely clamp the two members 12 and 18 against the post 11.

When it is desired to remove the terminal it is only necessary to insert a punch, screw driver, or similar tool, in the opening 21 and 60 pry the hinged member 18 upwardly as shown in Fig. 2. This can be easily done regardless 65 of the state of corrosion of the post and terminal.

After the hinged member 18 has been released the main terminal member 11 can be easily knocked or pulled from the battery 70 post. In use, the hinged member will eventually become corroded but can be easily and quickly renewed without the necessity of renewing the entire terminal.

In Fig. 3 I have illustrated an alternate 75 form of the invention in which the lug 17 is replaced by a tongue 21 which slides within a groove 22 in the main terminal member. The action of the alternate form is identical to the previously described form.

80 While a specific form of the improvement has been described and illustrated herein, it is desired to be understood that the same may be varied, within the scope of the appended claims, without departing from the spirit of 85 the invention.

Having thus described the invention, what is claimed and desired secured by Letters Patent is:

1. A terminal for connecting a battery cable to a battery post comprising: a first clamp member adapted to partially surround one side of a battery post; a second clamp member adapted to contact with the other side of said battery post; a clamp bolt pivoting said two members together adapted to bring said members into clamping engagement with said battery post; a tongue formed on said second clamp member adapted to swing into a vertically opening socket on said 90 95 100

first clamp member so that when said pivot bolt is loosened said second clamp member may be swung vertically to the axis of said battery post until it is released from said 5 socket; and means for attaching said cable to one of said members.

2. A battery cable terminal comprising: a first clamp member having a semi-cylindrical depression for receiving a battery post; a 10 cable socket on said first member; an ear formed on said first member; a second clamp member adapted to engage said battery post; a pivot passing through said ear and through one extremity of said second clamp member 15 so as to allow the latter to be swung upwardly parallel to the axis of said depression; and means for engaging the other extremity of said second clamp member to said first member when it is swung downwardly.

20 3. A battery cable terminal comprising: a first clamp member having a depression to receive a battery post; a cable socket on said first clamp member; a bolt ear on said first member; a second clamp member; a bolt 25 passing through said ear and one extremity of said second clamp member so as to provide a pivot for the latter; means on the other extremity of said second clamp member for detachably engaging said first clamp member 30 as said second member is swung downwardly into contact therewith so that when so engaged the tightening of said bolt will clamp both said members against said battery post.

25 4. A battery cable terminal comprising: a first clamp member having a depression to receive a battery post; a cable socket on said first clamp member; a bolt ear on said first member; a second clamp member; a bolt 40 passing through said ear and one extremity of said second clamp member so as to provide a pivot for the latter; means on the other extremity of said second clamp member for detachably engaging said first clamp member 45 as said second member is swung downwardly into contact therewith so that when so engaged the tightening of said bolt will clamp both said members against said battery post, said means comprising: a tongue upon one 50 of said members arranged to engage a socket in the other of said members, said socket opening vertically so as to allow the tongued member to be swung upwardly to release said post.

55 In testimony whereof, I affix my signature.
MOTTEL CLAR.
